(57) **CLAIM**

The ornamental design for a luminaire having multiple illumination panels, as shown and described.

DESCRIPTION

FIG. 1 is a plan view, as seen from below, of the luminaire having multiple illumination panels;

FIG. 2 is a perspective view, as seen from below, of the luminaire having multiple illumination panels; and

FIG. 3 is a plan view, as seen from below, of the luminaire having multiple illumination panels, with a first one of the illumination panels being illuminated from within; and,

FIG. 4 is a plan view, as seen from below, of the luminaire having multiple illumination panels, with a second one of the illumination panels being illuminated from within.

Light broken lines represent portions of the luminaire which form no part of the claimed design. Heavy broken lines represent an unclaimed boundary between the claimed design and those portions of the luminaire which form no part of the claimed design. The broken radiating lines which emanate from portions of the claimed design indicate only that the portion is illuminated, but otherwise form no part of the claimed design.
